UNITED STATES PATENT OFFICE

2,077,474

SHINGLE CUTTER

Severin N. Gundlach, Belleville, Ill.

Application April 1, 1936, Serial No. 72,011

6 Claims. (Cl. 164—14)

This invention relates to cutting devices, particularly portable shingle cutters of the kind shown in my Patent No. 1,814,151 dated July 14, 1931. The objects of the present invention are to provide a powerful device operable by the operating lever of the cutter for quickly and easily punching nail holes in the shingles and to provide for simplicity and cheapness of construction, compactness of design and the easy attachment of said device to said cutter. The invention consists in the shingle cutter and in the construction, combinations and arrangements of parts hereinafter described and claimed.

In the accompanying drawing, which forms part of this specification and wherein like symbols refer to like parts wherever they occur.

Fig. 1 is a side view of a shingle cutter embodying my invention.

Fig. 2 is a view of the other side of the shingle punching end of the cutter.

Fig. 3 is a fragmentary view similar to Fig. 1, showing the position of the parts during the operation of punching a shingle.

Fig. 4 is a fragmentary front end elevation of the cutter in the region of the punching device.

Fig. 5 is an enlarged fragmentary side elevation of the shingle cutter in the region of the punching device, the punch holder being shown partly in section.

Fig. 6 is a view similar to Fig. 5, showing the punch in engagement with a shingle, and

Fig. 7 is a section on the line 7—7 in Fig. 6.

The shingle cutter shown in the accompanying drawing comprises a stationary lower holder 1 provided near its ends with suitable supporting legs 2 and along its top with a suitable knife blade 3, and an upper holder 4 pivotally supported, as at 5, at one end of said lower holder and provided along its bottom with a knife blade 6 adapted to cooperate with the lower knife blade. The pivoted upper knife holder 4 is raised and lowered by means of a bent lever 7 having a short arm 8 pivotally connected by means of a horizontal pin 9 to the free end of said upper knife holder, a free long arm 10 constituting an operating handle, and a second short arm 11 pivotally connected by means of a horizontal pin 12 to the upper end of an upright link 13, whose lower end is secured by means of a horizontal pin 14 to the adjacent end of the stationary lower knife holder 1. By this arrangement, when the operating handle 10 of the lever 7 is swung downwardly, said lever pivots on the pin 12 at the upper end of the link 13 and thus swings the pivoted upper knife carrier 4 downwardly into

cutting position and, at the same time, causes said link to swing on the supporting pin 14 therefore toward the free end of said upper knife carrier.

The above shingle cutter is provided with a device for punching nail holes in the shingles. Said punching device comprises a punch holder or supporting bracket 15 mounted on the cutter opposite the free end of the pivoted knife holder 4 with its rear upper corner supported on the pivot pin 12 and with its rear lower corner supported on the pivot pin 14. The punch supporting bracket 15 is provided adjacent to its front end with an upwardly opening notch 16 that extends from side to side of said bracket. Mounted in a pocket or recess 17 provided therefor in the side face of the bracket 15 rearwardly of the notch 16 therein is a plunger or punch 18 adapted for axially sliding movement across said notch through a hole 19 leading thereto from the front end of said recess. The punch extends rearwardly from the pocket 17 through a hole 20 at the rear end thereof with its rear end disposed opposite a lug 21 on the free end of the pivoted knife holder 4. The punch is normally held substantially clear of the notch 16 by a coil spring 22 that is sleeved on said punch with one end abutting against the forward end wall of the pocket and with its rear end abutting against a washer 23, which is sleeved on the punch and is held against rearward movement thereon by means of a cotter pin 24, whose closed end works in an elongated slot 25 provided therefor in the side of the recess and serves to limit the rearward travel of the punch. The punch is provided with a tapered forward end portion 18a adapted to cooperate with a suitable die 26 mounted in an opening 27 provided therefor in the front wall of the shingle receiving notch 16. The opening 27 extends through the forward end of the punch holder 15 so as to permit the punching to be ejected from said opening at the forward end thereof.

By the arrangement described, when the operating arm of the knife operating lever is swung downwardly, the punch support 15 swings rearwardly with the link 13 about the axis of the pin 14 towards the front end of the pivoted knife carrier 4 until the rear end of the punch 18 is brought into abutting relation with the lug 21 on the front end of said knife carrier. Further rearward swinging movement of the punch support forces the punch axially against the pressure of the spring 22 across the notch 16 in said holder to cause its front end portion to enter

the die 26 in the front wall of said notch, thereby punching a hole in a shingle that has been positioned in said notch. The notch serves to support the weight of the shingle during the operation of punching the hole therein and it also locates said hole the required distance from the lower edge of the shingle. The punching device is strong and durable and is easily operated by the long handled knife operating lever of the 10 shingle cutter.

Obviously, the hereinbefore described construction admits of considerable modification without departing from the invention. Therefore, I do not wish to be limited to the precise construction 15 shown and described.

What I claim is:

1. A shingle cutter comprising a stationary 20 knife holder, a pivoted knife holder, means for actuating said pivoted knife holder including a member movable relative to said holders, and an axially slidible punch movable with said member into engagement with one of said holders to be moved into operative position thereby.

2. A shingle cutter comprising a stationary 25 knife holder, a pivoted knife holder, means for actuating said pivoted knife holder including a member movable relative to said holders, an axially slidible punch movable with said member into engagement with the free end of said pivoted 30 knife holder to be moved into operative position thereby, and a spring for returning said punch to inoperative position when the latter is disengaged from said pivoted knife holder.

3. A shingle cutter comprising a stationary 35 knife holder, a pivoted knife holder, means for actuating said pivoted knife holder including a member movable relative to said holders, an axially slidible punch movable with said member into engagement with the free end of said pivoted 40 knife holder to be moved into operative position thereby, and a spring for returning said punch to inoperative position when the latter is disengaged from said pivoted knife holder, said member being provided opposite the work engaging end of said punch with an upwardly opening 45 notch adapted to receive and support the shingle during the punching operation.

4. A shingle cutter comprising a stationary 50 lower knife holder, a pivoted upper knife holder, a link disposed opposite the free end of said upper knife holder with its lower end pivoted to

the corresponding end of said lower knife holder, a lever having an arm pivoted to the free end of said upper knife holder and an arm pivoted to the upper end of said link, whereby said link is adapted to swing towards said ends of said holders when said lever is actuated to move said pivoted holder into operative position, a punch holder pivotally secured to said lower knife holder at its point of connection with the lower end of said link and to said lever at its point of connection with the upper end of said link, and a punch axially slidible in said holder with one end in position to be forced against the free end of said pivoted holder when said lever is actuated to move said pivoted holder to operative 10 position.

5. A shingle cutter comprising a stationary 15 lower knife holder, a pivoted upper knife holder, a lever for operating said upper knife holder, a punch holder pivotally secured to said lower knife 20 holder opposite the free end of said pivoted knife holder and to said lever for movement thereby towards and away from said end of said pivoted knife holder, and a punch axially slidible in said holder in position to be forced against the free 25 end of said pivoted knife holder and moved into operative position thereby, when said lever is actuated to move said pivoted knife holder to operative position.

6. A shingle cutter comprising a stationary 30 lower knife holder, a pivoted upper knife holder, a lever for operating said upper knife holder, a punch holder pivotally secured to said lower knife 35 holder opposite the free end of said pivoted knife holder and to said lever for movement thereby towards and away from said end of said pivoted knife holder, a punch axially slidible in said holder in position to be forced against the free 40 end of said pivoted knife holder and moved into operative position thereby, when said lever is actuated to move said pivoted knife holder to operative position, and a spring mounted in said punch holder and cooperating with said punch 45 to return the same to inoperative position when the pivoted knife holder is moved to inoperative position, said punch holder being provided opposite the work engaging end of said punch with an upwardly opening notch adapted to receive and support the shingle during the punching 50 operation.

SEVERIN N. GUNDLACH.
